UNITED STATES PATENT OFFICE.

JOSEPH S. TURINS, OF CLEVELAND, OHIO.

OPERATING MECHANISM FOR ICE-CUTTING MACHINES.

1,345,290.

Specification of Letters Patent. Patented June 29, 1920.

Application filed February 1, 1916. Serial No. 75,583.

To all whom it may concern:

Be it known that I, JOSEPH S. TURINS, a citizen of the United States, residing at Cleveland, in the county of Cuyahoga and State of Ohio, have invented certain new and useful Improvements in Operating Mechanism for Ice-Cutting Machines; and I do hereby declare the following to be a full, clear, and exact description of the invention, such as will enable others skilled in the art to which it appertains to make and use the same.

This invention relates to ice cutting machines, and the primary object of this invention is to provide a motor driven ice cutting machine which includes a novel construction for operating the rear driving axle of the ice cutting machine through the medium of the power transmitting structure employed for rotating a crank shaft operating ice cutting saws.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:—

Figure 1 is a side elevation of the ice cutting machine showing parts broken away, and

Fig. 2 is a fragmentary horizontal section of the ice cutting machine.

Referring more particularly to the drawings, 1 designates the supporting platform or base of the ice cutting machine as an entirety, which has a prime mover 2 mounted thereon. The prime mover 2 may be either an electrical motor, a gasoline engine or any other desired type of prime mover, this feature being left to the desire of the person manufacturing the device.

The prime mover 2 has a main power shaft 3 operatively connected thereto and this shaft will carry a conventional gearing (not shown) so that rotary movement may be transmitted through the medium of gear 8 to the shaft 9.

The shaft 9 extends transversely to the shaft 3 and is rotatably supported by a suitable pillow block 10. The shaft 9 has a

beveled gear 11 mounted thereupon which meshes with the beveled teeth formed upon a gear member 13 rotatably mounted upon a shaft 14. The gear member 13 has ordinary gear teeth 17 formed thereupon which mesh with a pinion 18. The gear 18 meshes with a gear 21, which is mounted upon a crank shaft 22. The crank shaft 22 is positioned at the rear end of the supporting platform 1 and is rotatably supported by suitable bearings 23 and has ice cutting saws 25 connected thereto and extending downwardly through openings 26 which are formed in the supporting base 1. The saws 25 are loosely connected to the crank extensions of the crank shaft 22, so they will maintain a vertical position at all times during the rotation of the crank shaft and move vertically through the ice for cutting the same.

The supporting platform 1 has hangers 27 connected to its under surface adjacent the rear ends, which hangers rotatably support the drive axle 28 of the ice sawing machine. The axle 28 has wheels mounted thereon for rotation with the axle, which wheels have a plurality of spaced spurs extending about their peripheries, for biting into the ice for propelling the ice sawing machine. Outstanding rings or flanges 31 extend annularly about the rims of the wheels 29 and are provided for preventing sidewise slipping of the wheels and the ice sawing machine.

The axle 28 has a relatively wide ratchet wheel 32 mounted thereon intermediate its ends, the peripheral ratchet teeth 33 of which are provided for coaction with a pawl 34 carried by a bar 35. The bar 35 has its upper end mounted upon a pin 36, which pin is eccentrically connected to the gear member 13, as clearly shown in Fig. 1 of the drawings, so that during the rotation of the gear member 13, the pawl 34 will be brought into and out of engagement with the ratchet teeth 33, and rotate the axle 28 by the rotation of the gear member 13 which member also acts to transmit the power to the crank shaft 22, thereby controlling the rotation of the axle 28 with the rotation of the crank shaft 22, for properly controlling the speed of the forward movement of the ice sawing machine.

A shifting rod 40 which is provided with

an upstanding shifting handle 44 is slidably carried by the upper surface of the supporting platform 1 and it has one end provided with an eye through which the bar 35 extends, thus providing means whereby the bar 35 may be moved into an inoperative position for moving the pawl 34 out of operative relation to the ratchet wheel 32, and further providing means for guiding vertical movement of the bar when in operation.

The ice sawing machine is steered, through the medium of a steering post 50 which projects vertically through the supporting platform 1, and has a steering wheel 51 mounted upon its upper end. The steering post 50 is operatively connected to the axle bearings 54, of the front axle 55 thus permitting the skein or truck 57 to be swung for guiding the direction of travel of the ice sawing machine, as is ordinary in the construction of steering mechanism of this nature. The steering post 50 has an arm 60 mounted thereon, and positioned above the platform 1, which arm has an opening 61 formed therein adjacent its outer end. The arm 60 travels above the upper surface of a quadrant 62, which is carried in a horizontal plane by a suitable supporting structure indicated at 63. The quadrant 62 is provided with a plurality of spaced openings, through which a pin passed through the opening 61 may be passed for holding the arm in various adjusted positions about the quadrant for holding the steering post 50 against accidental movement, and preventing the slipping of the steering wheels of the ice cutting machine during travel over an ice field. The supporting wheels 66 which are mounted upon the front axle 55 have peripheral flanges 67 formed centrally of their rim sec-

tions which are provided for preventing lateral creeping or slipping of the wheels.

From the foregoing description taken in connection with the accompanying drawings the advantages of construction and of the method of operation of the improved ice cutting machine will be readily apparent to those skilled in the art to which this invention appertains and, while in the foregoing description, the principle of the operation of this invention has been described together with various features of construction, it is to be understood that certain minor features of construction combination and arrangement of parts may be altered to suit practical conditions provided such alterations are comprehended within the scope of what is claimed.

What is claimed is:—

In propelling means, a rotatable gear, an axle mounted below the gear, a ratchet wheel secured on said axle, a bar eccentrically secured at its upper end to the gear, a control rod mounted for movement toward and away from the gear and provided with an eye slidably receiving said bar so as to guide the same during reciprocation thereof, the lever serving to hold the bar in adjustment toward, and away from the ratchet wheel, and a pawl rigidly secured to said bar adjacent the lower end thereof and adapted to engage the ratchet wheel so as to impart intermittent rotation thereto when the gear is rotated.

In testimony whereof I affix my signature in presence of two witnesses.

JOSEPH S. TURINS.
